UNITED STATES PATENT OFFICE.

JAMES A. BURNS, OF HOMESTEAD, PENNSYLVANIA.

LADLE-CAR.

SPECIFICATION forming part of Letters Patent No. 439,637, dated November 4, 1890.

Application filed January 17, 1890. Serial No. 337,172. (No model.)

To all whom it may concern:

Be it known that I, JAMES A. BURNS, of Homestead, in the county of Allegheny and State of Pennsylvania, have invented a new 5 and useful Improvement in Ladle-Cars, of which the following is a full, clear, and exact description, reference being had to the accompanying drawings, forming a part of this specification, in which—

10 Figure 1 is a plan view of my improved ladle and car. Fig. 2 is a side elevation thereof, the ladle being shown lifted from the car. Fig. 3 is a side elevation of the ladle and car. Fig. 4 is a vertical cross-section on the line 15 IVIV of Fig. 3. Fig. 5 is an end view of the ladle and car, shown partly in section. Fig. 6 is a plan view, showing the use of the ladle in the ladle-pit.

Like symbols of reference indicate like 20 parts in each.

In the drawings, 2 represents the car-body or frame, which is preferably made of a single casting of iron or steel. It consists of end pieces or platforms resting upon the wheel- 25 trucks 3, to which they are secured by king-bolts 4, and a connecting opossum-belly or middle portion, which is of downwardly-bowed form and is preferably of the cross-sectional shape shown in Fig. 4, having a horizontal web 30 and two parallel flanges projecting vertically in both directions from intermediate parts thereof. This form imparts very great strength to the car, the upper flanges of the opossum-belly being in a state of compression and the 35 lower flanges being in a state of tension, or vice versa, accordingly as the strain imparted to the car is a pulling force or a pushing force or bump.

6 is the ladle, which is carried by the car. 40 Its body is made of form suitable to the work for which it is designed, and is provided with lugs or straps 7 for the attachment of the chains of a crane, by which it may be lifted from the car or lowered into place thereon.

45 8 are trunnions which project from diametrically-opposite points on the sides of the ladle. Each of these trunnions is provided with an enlarged base or foot 9, suitably braced by projecting ribs or webs and firmly 50 secured to the ladle by rivets or otherwise. Each trunnion has cast in the same piece or attached to it a segmental gear-wheel 10, and

adjacent thereto a plain wheel 11, having a crown-face, the periphery of which is about coincident with the pitch-line of the gear- 55 wheel.

The ladle is supported by blocks 12, set on the platform of the car above the trucks. Each of these blocks is preferably made of a single casting, secured to the body of the car by bolts 6c 13 and having formed on its surface a transverse rack or toothed portion 14, and a plain-faced portion 15, situate beside the rack. When the ladle is set in position on the car, the crown-faced wheels 11 rest upon the parts 65 15 of the blocks 12 and the toothed wheels or segments 10 fit upon the racks, being guided into position thereon by projections 5 formed on the blocks. The weight of the ladle is, however, borne by the wheels 11, which support it sufficiently to clear the teeth of the gear-wheels from the bottom of the racks, the purpose of this construction being to diminish the friction between the racks and the gear-wheels in the operation of tipping the ladle. 70 The line of bearing of each of the crown-faced wheels on the block 12 is preferably directly above the middle of the car-truck where the bolster-pin passes through the latter, and as the entire weight of the ladle is 75 borne by these wheels it is transmitted to the trucks at these points.

16 is a screw, which extends across the car-frame and has its bearings in journal-boxes 17, which project from the block 12 and are 80 provided with caps 18. The screw is provided with collars 19, which prevent its endwise motion, and at its ends it is squared, so as to enable it to be turned by a spanner or wrench of the usual form. At the other end of the 85 car-frame is a plain bar 20, arranged parallel with the screw 16 and supported in a similar manner.

21 and 22 are blocks through which the screw 16 and the bar 20 respectively pass. It is 90 not necessary that these blocks should be supported otherwise than by the screw and bar, and I therefore prefer that their bases should slightly clear the surfaces of the blocks over which they are placed. The hole in the block 100 21 through which the screw 16 passes is threaded, as shown in Fig. 5, but the hole in the block 22 through which the bar 20 passes is plain. The block 21, therefore, performs the

function of a nut on the screw-shaft 16. The surfaces of the blocks 21 and 22 are forked, so as to accommodate the trunnions 8, which fit within them; but, as shown in Fig. 5, the 5 trunnions do not bear upon the bases of the forked portions.

I shall now describe the operation of the parts of the apparatus in tipping the ladle.

In Figs. 1 and 3 and in full lines in Fig. 5 10 the ladle is shown in an upright position upon the car. In order to tip it the screw 16 is turned in its bearings, the effect of which is to move the nut 21 across the car-frame, and as the trunnions of the ladle fit between the 15 forks of this nut the ladle itself is pushed laterally and carries with it the block 22 at the other end of the car. The weight of the ladle is borne by the crown-faced wheels 11, and the action of these wheels, together with 20 the toothed wheels 10 and racks 14, is to cause the ladle to turn on the axis of its trunnions simultaneously with its lateral motion, and because the weight is borne by the crown-faced wheels there is no such substantial 25 pressure on the screw or on the gear-wheels as to produce undue friction and to impede their action. The function of the nut 21 is simply to carry the ladle laterally, not necessarily to support it. The function of the block 30 22 and its shaft is to guide and steady the ladle in its lateral motion. The function of the crown-faced wheels is to support the ladle and to remove the weight thereof from the other parts, and the function of the rack and 35 toothed wheels is to assist in producing the rotary motions above noted and to insure perfect steadiness and uniformity in action of both sides of the ladle.

The reason for providing the wheels 11 40 with rounded or crown faces is that they may be able to adjust themselves to the faces of the blocks 12, so as to sit evenly thereon, even though from warping of the ladle or car from any other cause the positions of the 45 wheels and the bearing-faces on the blocks be not exactly uniform. The lateral motion and tipping of the ladle may be continued until the parts are brought into the position shown by dotted lines in Fig. 5, when the 50 ladle will have performed a quarter-revolution, so as to bring its side into a vertical position and to cause the discharge of its entire contents; or, if desired, the lateral motion of the nut 21 may be continued far enough only 55 to partially tip the ladle and to cause the discharge of a part only of its contents. In either case the tipping of the ladle is accompanied by its lateral movement on the car-frame, the effect of which is to dump the contents entirely clear of the car and of the track 60 on which the car travels. This feature of my improvement is one of great importance, and will be appreciated as such by those familiar with the difficulties attending the tipping of 65 molten slag and metal from a ladle incapable of such lateral motion. When the contents of the ladle have been discharged, it may be

brought back into a horizontal position in the middle of the car by simply turning the screw in a reverse direction. It will be noticed that the ladle may be tipped on either side of the car, its motion to one side or the other being governed by the direction of rotation of the screw. As the parts are arranged in Fig. 5 the complete tipping of the ladle is 70 effected when it has moved to the extreme limit of its lateral travel. It may, however, be caused to tip before the nut has reached the end of the screw by setting the nut to one side of the middle of the latter before placing 80 the ladle in a horizontal position on the car.

When the ladle is used for conveying slag or molten metal from a furnace to the place of discharge, it may be lifted completely from the car by means of a crane, the chains of 85 which may be attached as shown in Fig. 2, and when it has received its charge of slag or metal it may be lowered upon the car, as shown in Fig. 3, so that the trunnions shall fit within the forks of the nut 21 and block 90 22. In order to hold the block 22 in proper position relatively to the nut, I prefer to employ a hook or catch 23, which is pivoted to the car-body at the middle point of the lateral motion of the block and is adapted to 95 be moved to engage a notch therein and thereby to lock it in position.

In lifting the ladle from the car, as above described, the ladle is removed freely from the trunnion carriers or blocks, leaving its operative mechanism (the screws, &c.,) on the car-body. The ladle is therefore unencumbered with mechanical parts—such as worm-gearing and cranks—by which its use in the ladle-pit would be impeded. The easy 105 removability and detachability of the ladle from the car and from the mechanism which moves it laterally, effected by the fixing of such mechanism to the car-body and by setting the ladle-trunnions removably in their 110 carriers, are features of material importance, and are claimed by me, broadly, herein.

In Fig. 6 I show the manner of use of the ladle in receiving the slag from the casting-ladle in the ladle-pit. At opposite sides of 115 the casting-pit I form laterally-open sockets 25, which are of squared shape in cross-section, so as to be adapted to receive the ends of the trunnions 8. The ends of these trunnions are squared, and when the ladle is lowered into the casting-pit, so that the trunnions shall fit in the sockets and shall rest on the bases thereof, it is effectively prevented from 120 tipping. During the operation of casting, the slag-ladle is set in these sockets in the casting-pit, and after the metal has been discharged into the molds from the casting-ladle the latter is brought over the slag-ladle, the 125 slag is discharged into it, and then the slag-ladle with its burden of slag may be lifted by 130 a crane and placed on the car, as above described. It is also desirable to employ grapping-chains 24, which are attached to the rails of the track during the act of tipping

the ladle, (see Fig. 5,) so as to hold the car and to prevent upsetting thereof in consequence of the change in the center of gravity produced by the lateral motion of the ladle. 5 These grappling-chains I do not claim as of my invention.

If it be found desirable at any time to discontinue the use of the car as a means for carrying the ladle and to use it for carrying ingots or other burdens, the ladle may be removed and the car dismantled by removing the journal-caps of the screw 16 and bar 20 and taking out this bar and screw, or the car may be further dismantled by unbolting and 15 removing entirely the blocks 12. The car-frame will then present no obstruction to its use as an ingot-car or for any purpose to which it may be adapted.

The advantages of my improvement will be 20 appreciated by those skilled in the art.

The ladle-car is simple in its construction, not liable to get out of order, and the facilities which it affords for dumping its burden clear of car and track and on either side 25 thereof render it very useful in iron and steel mills for removing slag from furnaces or for transporting molten metal from one place to another.

The improvement is susceptible of many 30 modifications in form and arrangement of the parts, such as will be suggested by the foregoing description to the skilled mechanic. All such modifications I intend to cover by the following claims, which severally and independently set forth the new and patentable 35 features of the invention.

I claim as my invention—

1. The combination, with a car, of a tipping ladle having trunnions, laterally-movable 40 trunnion-carriers in which the trunnions are removably set, and mechanism fixed to the car-body connected with the trunnion-carriers and operative to move them laterally, substantially as and for the purposes described. 45

2. The combination, with a car, of a ladle set on the car on wheels fixed to the ladle, laterally-movable blocks or nuts for the ladle-trunnions, and a screw mounted on the car 50 and passing through one of the blocks or nuts, whereby the ladle may be moved laterally on the car and tipped, substantially as and for the purposes described.

3. The combination, with a car having end 55 trucks, of a frame or body with a bowed opossum-belly mounted on the trucks and permanently connecting them, a ladle having trunnions, and trunnion-supports on the frame or body by which the ladle is removable 60 ably upheld, substantially as and for the purposes described.

4. A car frame or body having its middle portion of cross-sectional form, substantially as shown in Fig. 4.

5. The combination, with a car, of a ladle 65 set on the car on wheels fixed to the ladle, laterally-movable blocks or nuts for the ladle-trunnions, a screw mounted on the car and passing through one of the blocks or nuts, whereby the ladle may be moved laterally on 70 the car and tipped, and a plain bar passing through the other block or nut, substantially as and for the purposes described.

6. The combination, with a car, of a ladle 75 set on the car on wheels fixed to the ladle, laterally-movable blocks or nuts for the ladle-trunnions, a screw mounted on the car and passing through one of the blocks or nuts, whereby the ladle may be moved laterally on 80 the car and tipped, a rack on the car, and a toothed segment on the ladle in gear with the rack, substantially as and for the purposes described.

7. The combination, with a car, of a tipping 85 ladle having trunnions, laterally-movable trunnion-carriers from which the ladle is freely removable, and mechanism by which the carriers are moved laterally on the car-body, substantially as and for the purposes described. 90

8. The combination, with a car, of a laterally-movable tipping ladle, trunnion-carriers by which the ladle is moved laterally on the car, and crown-faced wheels by which the ladle is supported, substantially as and for 95 the purposes described.

9. The combination, with the car-frame or body, of blocks 12, removably secured thereto and adapted to carry or support a ladle, substantially as and for the purposes described. 100

10. The combination, with the car frame or body, of blocks 12, removably secured thereto and adapted to carry or support a ladle, one at least of said blocks having a toothed portion or rack, and journals in which a screw-shaft may be carried, substantially as and 105 for the purposes described.

11. The combination of the car, the removable ladle having a gear-wheel, and a rack on the car having a projection to guide the 110 gear-wheel into place in the rack, substantially as and for the purposes described.

12. A ladle having trunnions with squared portions by which the ladle may be prevented from tipping, substantially as and 115 for the purposes described.

In testimony whereof I have hereunto set my hand this 1st day of November, A. D. 1889.

JAMES A. BURNS.
